COLLAPSIBLE CAMP STOVE

Peter Thoreson, Aberdeen, Wash.

Application August 5, 1936, Serial No. 94,320

2 Claims. (Cl. 126—9)

My invention relates to improvements in collapsible camp stoves and the main object is to provide a camp stove made up of a number of flat metal pieces so cut and formed that they may be set up quickly and conveniently to form an efficient cooking and heating stove for the camp or for emergency use in the house and in which the pieces may be collapsed and formed into a flat compact bundle for carrying and storage.

Another object is to provide a stove of this kind including a bottom having upturned marginal flanges, a back placed upright in the bottom and having forwardly turned flanges on its lateral edges, sides placed upright on the bottom inwardly of the flanges on both bottom and back, a top having flanges turned down over the sides and back and having a forwardly projecting ear on its frontal end, and a front or cover having slots any of which will engage the said ear to hold the front in place and to vary the draft, and a smoke escape means in the top.

A further object is to provide an assembly of this kind including simple and convenient means for holding the parts assembled.

With these and other objects in view the invention resides in the novel construction and arrangement of parts as hereinafter fully set forth and claimed, reference being had to the accompanying drawings as showing a preferred embodiment of my invention for purposes of exemplification.

In the drawings:

Figure 1 is a perspective view of the stove set up for use.

Figure 2 is a perspective view of the bottom alone.

Figure 3 is a perspective view of the top alone.

Figure 4 is a perspective view of one of the sides.

Figure 5 is a perspective view of the back alone.

Figure 6 is a fragmental enlarged cross section through one side portion of the stove showing one of the lock pins in use for holding the stove assembled.

In carrying out my invention I provide first a bottom or base member 10 of sheet metal of any suitable kind and gauge and of rectangular shape with upturned marginal flanges 11 around both sides 12 and 13 and front and rear ends 14 and 15. Two identical sides 16 are provided in rectangular shape and of such size that they may be set upright on their lower edges on the bottom 10 within the flanges 11. A back 17 is provided

and same is of such width as to set on edge across the rear end of the bottom 10 inwardly of the flanges 11 and this back has forwardly turned flanges 18 along its vertical lateral edges which overlie the rear end of the sides 16. A top 19 is provided of substantially the same size and shape as the bottom 10 and has downwardly turned flanges 20 along its sides 21 and 22 and rear end 23 which flanges will overhang the upper margins of the sides 16 and back 17. At its frontal end 24 at the center thereof the top 19 has a wide short support ear or tongue 25 forwardly projected and near its rear end 23 an aperture 26 is cut out and the margins 27 thereof split as shown at 28 so that they may be turned up to form an annular collar on which a smoke pipe (not shown) may be fitted.

A front or cover 29 is provided and same is of flat rectangular shape substantially larger than the back 17. This front has a plurality of vertically spaced and horizontally elongated slots 30 cut in its central upper portion and any one of the slots may receive the ear 25 and support the front on the stove. A U-shaped wire handle 31 is secured by its ends 32 to the front 29 near its upper margin.

The top 19 has apertures 33 spaced inward a short distance from the flanges 20 and these apertures receive lock pins 34 which in the assembly will slip down nicely inside the upper margins of both the sides 16 and back 17 and so hold these parts from falling inwardly. Heads 35 on the pins 34 prevent their falling through into the stove and to prevent their loss or misplacement the pins may be attached to the top 19 by short cords or chains (not shown) if so desired.

When not in use the various parts of the stove all being flat may be collapsed and stacked in a nested compact and readily carried bundle. To set the stove up the bottom 10 is simply placed on some level support and the sides 16 and back 17 set up, the top 19 placed thereon and the pins 34 inserted. When the fire is built in the stove the front 29 may be put in place and by using the proper one of the slots 30 to hang the front on the ear 25; an opening 36 may be left at the bottom to allow any desired draft through the stove. The sides, back, top and front of the stove are all made of sheet metal of any suitable gauge and kind. If desired lock pins may be inserted also through the back 17 to hold the sides 16 from slipping inwardly at their lower edges.

While I have herein set forth a certain preferred embodiment of my invention, it is under-

stood that I may vary from the same in minor structural details so as best to provide a practical device for the purposes intended, not departing from the spirit of the invention and within the scope of the appended claims.

I claim:

1. In a stove, a bottom with upstanding marginal flanges, sides set on edge on the bottom within the flanges, a back set on edge on the bottom, flanges turned forwardly from the back alongside the rear ends of the sides, a top, flanges turned downwardly from the top over the upper margins of the sides and back, an ear extended forwardly from the frontal end of the top, a front having spaced slots any of which is adapted to receive the said ear and support the front in place.

2. In a stove, a bottom with upstanding marginal flanges, sides set on edge on the bottom within the flanges, a back set on edge on the bottom, flanges turned forwardly from the back alongside the rear ends of the sides, a top, flanges turned downwardly from the top over the upper margins of the sides and back, an ear extended forwardly from the frontal end of the top, a front having spaced slots any of which is adapted to receive the said ear and support the front in place, the said top having a smoke pipe opening adjacent its rear end, and having apertures spaced inwardly from its flanged margins and lock pins adapted to be passed down through the apertures inwardly of the said upper margins of the sides and back. 5 10 15

PETER THORESON.
